ROCK DRILL

John C. Curtis and Elmer G. Gartin, Claremont,
N. H., assignors to Sullivan Machinery Company,
a corporation of Massachusetts

Application September 18, 1941, Serial No. 411,283

16 Claims. (Cl. 255—51)

This invention relates to rock drills and particularly to improvements in a guide for the drill steel of a hammer rock drill.

An object of the present invention is to provide an improved drill steel guide. Another object is to provide an improved drill steel guide having novel locking means for locking the guiding means in guiding position, and novel means for automatically moving the guiding means into non-guiding position when the locking means is released. A further object is to provide an improved drill steel guide of the pivoted arm type having improved means for locking the guide arms in guiding position and for automatically swinging the guide arms into their released non-guiding position when the locking means is released. A still further object is to provide an improved guide locking means which is releasable by engagement of the drill hammer motor therewith as the latter moves along its supporting guide. Yet another object is to provide an improved torsion spring arrangement for automatically effecting swinging of the guiding arms apart when the arm locking means has been released. Another object is to provide an improved drill steel guide of the pivoted guide arm type wherein the guide arms may be individually swung about their pivots into guiding relation with the drill steel, and having individual locking means. It is still a further object to provide a novel locking arrangement for the guide arms of a drill steel guide. How these and other objects are accomplished, and the advantageous features of the invention, will be best understood from the following detailed description wherein a preferred and illustrative embodiment is set forth, reference for this purpose being had to the accompanying drawing, in which:

Fig. 1 is a fragmentary side elevational view of the hammer rock drill with which the improved drill steel guide is associated.

Fig. 2 is a cross sectional view taken substantially on line 2—2 of Fig. 1, showing the guide arms in guiding position.

Fig. 3 is a sectional view similar to Fig. 2, showing the guide arms in their released non-guiding position.

Fig. 4 is a cross sectional view taken substantially on line 4—4 of Fig. 1.

Fig. 5 is a detail cross sectional view taken substantially on line 5—5 of Fig. 1.

Fig. 6 is a detail view in longitudinal vertical section taken substantially on line 6—6 of Fig. 2.

In this illustrative embodiment of the invention, the improved drill steel guide, generally des-

ignated 1, is shown associated with a conventional hammer rock drill of the mounted drifter type. It will be evident, however, that the improved drill steel guide may be associated with drills of other types.

The hammer rock drill comprises a conventional drill hammer motor 2 slidably guided on a conventional supporting guide 3 commonly known as a guide shell, the latter adapted to be mounted on a conventional drill support. The drill hammer motor has a motor cylinder 4 containing a reciprocable hammer piston (not shown) for percussively actuating a drill steel 5, the latter being supported in a usual chuck within a front chuck housing 6 suitably attached to the front end of the motor cylinder. The hammer motor cylinder has usual lateral guides 7, 7 slidably received within the longitudinal guideways 8, 8 of the guide shell. The hammer motor 10 may be fed in a well-known manner along the shell guideways by means of a conventional feed screw engaged with a feed nut carried by the motor cylinder so that when the feed screw is rotated, the motor is fed longitudinally relative to the guide shell. Since, as above stated, the rock drill is of a conventional design and is well known to those skilled in the art, further description and illustration thereof are unnecessary.

Now referring to the improved drill steel guide, it will be observed that attached by bolts 9, herein preferably three in number, to the front end of the guide shell 3 is a transverse rear plate 10, herein preferably having an integral bearing portion 11 in which the front bearing portion 12 of the feed screw is journaled. Spaced forwardly from the rear plate 10 is a parallel front plate 13 likewise secured to the guide shell by the bolts 9, and these plates are held in proper spaced relation by spacing sleeves 14 interposed between the plates on the bolts 9. Pivotally mounted on the spacing sleeves of the upper pair of bolts is a pair of cooperating guide arms 15, 15 each having an appropriately shaped guiding portion 16. These guide arms are identical in shape and design and are readily interchangeable so that a single forging design serves for both arms thereby to reduce the cost of manufacture. The guiding portions 16 of these guide arms are adapted to embrace the body of the drill steel 5 to hold the latter centered during starting or "spotting" of a hole, in the manner well known to those skilled in the art. The guide arms 15 are also mounted on the spacing sleeves of the upper bolts for bodily sliding movement between the plates, and the arms have rearwardly project-

ing locking lugs 17 engageable with locking projections 18 integral with the rear plate 10. The opposite sides of the rear plate are cut away at 19 in adjacency to the locking projections 18 so that the lateral guides 7 of the drill hammer motor may move forwardly past the rear plate when the guide arms are in their wide open non-guiding position. Coil springs 20 encircling the spacing sleeves of the upper bolts between the guide arm hubs and the front plate, act on the guide arms to hold the latter in their rearmost position with the locking lugs 17 in locking engagement with the locking projections 18 on the rear plate, the guide arms when in their rearmost position abutting the front face of the rear plate in the manner shown. A torsion spring 21 encircling the spacing sleeve of the lower bolt intermediate the arm pivots has its ends respectively engaging depending armlike lugs 22 integral with the guide arms, and this torsion spring serves automatically to move the guide arms into their released non-guiding position when the locking lugs are released from the locking projections. Surfaces 23 on the lugs 22 are engageable with abutment surfaces 24 on the rear plate 10 to limit outward swinging movement of the guide arms. The springs 20 acting on the guide arms hold the latter in frictional contact with the rear plate, so that the arms are held in their released position with the surfaces 23, 24 in abutting engagement. As shown in Fig. 6 the ends of the torsion spring 21 are connected to the lugs 22 by means of pins 25 fitted within bores 26 in the lugs.

In the operation of the improved drill steel guide, when it is desired to start or "spot" a drill hole the guide arms 15 may be swung about their pivots into the position shown in Figs. 1, 2 and 4 with the guiding portions 16 in engagement with the drill steel 5, and, at that time, the guide arms are locked in guiding position by engagement of the locking lugs 17 with the locking projections 18 on the rear plate (see Fig. 5). As the drill hammer motor is fed forwardly along the shell guideways, the front chuck housing 6 engages the rear surfaces of the guide arms and shoves the arms forwardly bodily along the spacing sleeves on which they are mounted, to effect release of the locking lugs 17 from the locking projections 18. When the guide arm locks are released, the torsion spring 21 acts automatically to throw the guide arms into the wide open non-guiding position shown in Fig. 3, so that the drill hammer motor can move forwardly between the guide arms without interference therewith. Under certain conditions the guide arms may be individually placed in guiding relation with the drill steel so that but a single guide arm may serve as a guide, for instance, during "spotting" of a drill hole on an inclined surface. A single guide arm may serve to guide the steel at this time since the steel tends to move laterally only in the direction of the incline. When it is again desired to position the guide arms in guiding relation with the drill steel, the operator may manually swing the arms against the tension of the torsion spring into guiding relation with the drill steel and then shove the guide arms bodily rearwardly into abutting engagement with the rear plate 10, with the arm locking lugs in engagement with the locking projections.

As a result of this invention, it will be noted that an improved drill steel guide is provided which is not only relatively simple in design, but also rugged in construction. It will further be

evident that by mounting the guide arms in the manner disclosed, the locking means is simplified and further by the provision of the torsion spring the guide arms are automatically thrown into their released non-guiding position. By means of this particular mounting arrangement for the guide arms, the latter are released by direct engagement of the chuck housing of the drill hammer motor therewith, thereby eliminating relatively complicated release devices. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a drill steel guide, a guide element engageable with a drill steel, mounting means for said guide element providing for pivotal and translatory movements thereof, locking means for holding said element in guiding position, said locking means being releasable upon translatory movement of said element, resilient means for yieldingly holding said guide element in locked position, and resilient means separate and distinct from said first mentioned resilient means for automatically swinging said guide element about its pivot into its released non-guiding position when said locking means is released.

2. In a drill steel guide, a support, a pair of guide arms mounted on said support for pivotal and translatory movements, locking means on said arms and support for locking said arms in guiding position, said locking means being releasable upon translatory movement of said arms relative to said support, and a torsion spring arranged on said support intermediate the pivotal axes of said guide arms and engaging both of the latter for automatically swinging said arms apart about their pivots when said locking means is released.

3. In a drill steel guide, a support including parallel plates, bolts for securing said plates together and spacing sleeves on said bolts for maintaining said plates in proper spaced relation, a pair of guide arms pivotally mounted and also slidably mounted for translatory movement on the spacing sleeves on two of said bolts, locking lugs on said guide arms engageable with locking projections on one of said plates, springs encircling the spacing sleeves on which said arms are mounted for yieldingly urging said arms in a direction to hold said lugs in locking engagement with said projections, said arms being slidable translationally against the action of said springs to effect release of said lugs from said projections, and a torsion spring encircling the spacing sleeve of the third bolt and engaging said arms for automatically swinging the latter about their pivots into their released non-guiding position when said locking lugs are released from said projections.

4. In a drill steel guide, a support, a pair of relatively movable guide arms mounted on said support to swing relative thereto into and out of guiding relation with a drill steel and for translatory movement longitudinally relative to the steel, means on said support and guide arms for positively locking the latter to said support in

steel guiding position and releasable upon translatory movement of said arms in one direction relative to said support, spring means for moving said arms translationally in the opposite direction relative to said support to hold said locking means in locking position, said arms being movable translationally in said one direction against the action of said spring means to effect release of said locking means, and spring means other than said first mentioned spring means for swinging said arms out of guiding relation with the drill steel when said arms are moved translationally into unlocked position.

5. In a drill steel guide, a support, a pair of relatively movable guide arms mounted on said support to swing relative thereto into and out of guiding relation with a drill steel and for translatory movement longitudinally of the steel, means for locking said arms in steel guiding position to said support and releasable upon translatory movement of said arms in one direction, and a common torsion spring mounted on said support intermediate the arm pivots for swinging said arms out of guiding relation with the drill steel upon translatory movement of said arms into unlocked position.

6. In a drill steel guide, a support, a pair of relatively movable guide arms, means for mounting said arms on said support for pivotal and translatory movements, means for positively locking said arms in guiding position to said support, means for moving said arms translationally in one direction yieldingly into locked position and yieldingly to hold said arms in locked position, said locking means being releasable upon translatory movement of said arms in the opposite direction relative to said support against the action of said yielding means, and means distinct from said yielding means for swinging said arms into their wide open non-guiding position upon translatory movement of said arms into unlocked position.

7. In a drill steel guide, a support comprising front and rear members held together in parallel spaced relation by a plurality of spaced parallel securing elements, a pair of guide arms mounted on two of said securing elements for pivotal and translatory movements, locking means on said support and arms for locking the latter in guiding position, said locking means being releasable upon translatory movement of said arms on said two securing elements, and a torsion spring encircling a third of said securing elements and engaging said arms for automatically swinging the latter about their pivots when said locking means is released.

8. In a drill steel guide, a support comprising front and rear members held together in parallel spaced relation by a plurality of spaced parallel securing elements, a pair of guide arms mounted on two of said securing elements for pivotal and translatory movements, locking means on said support and arms for locking the latter in guiding position, said locking means being releasable upon translatory movement of said arms on said two securing elements, springs on said two securing elements respectively for constantly urging said arms into locked position, said locking means being releasable against the action of said springs, and a torsion spring encircling a third of said securing elements and engaging said arms for automatically swinging the latter about their pivots when said locking means is released.

9. In a drill steel guide, a support, a guide ele-

ment mounted on said support for movements with respect thereto in different angularly related directions, one of said movements being translatory, locking means for locking said guiding element in steel guiding position to said support, means for yieldingly moving said guiding element translationally to hold said guiding element in locked position, said locking means being releasable upon translatory movement of said guiding element against the action of said yielding holding means, and means on said support other than said yielding means and operative upon translatory movement of said guiding element into a position wherein said locking means is released for moving said guiding element in a different direction into its non-guiding position.

10. In a drill steel guide, a support, a pair of relatively movable guide arms mounted on said support to swing relative thereto into and out of guiding relation with a drill steel and for translatory movement longitudinally of the steel, means for yieldingly moving said arms translationally in one direction into a position wherein said arms are held against swinging movement relative to said support in steel guiding position, said arms being movable translationally in the opposite direction against the action of said yielding means into a position wherein said holding means is ineffective, and means other than said yielding means for swinging said arms outwardly relative to each other into their wide open non-guiding position when said arms have moved translationally into a position wherein said holding means is ineffective, and said yielding means also serving yieldingly to hold said arms in their wire open non-guiding position.

11. In combination, a guide shell having guideways for slidably receiving the guides of a drill steel actuator, a support secured to the front end of said guide shell and having projections in advance of the shell guideways, said projections having cut-away portions in alinement with said guideways providing openings into which the guides on said actuator are adapted to move, and guiding means for the drill steel of said actuator mounted on said support and movable relative thereto into and out of steel guiding position.

12. In combination, a guide shell having guideways for slidably receiving the guides of a drill steel actuator, a support secured to the front end of said guide shell and having projections in advance of the shell guideways, said projections having cut-away portions in alinement with said guideways providing openings into which the guides on said actuator are adapted to move, and guiding means for the drill steel of said actuator mounted on said support and movable relative thereto into and out of steel guiding position, and said projections also providing abutment surfaces with which surfaces on said guiding means are engageable for holding said guiding means in steel guiding position.

13. In a drill steel guide, a support including spaced front and rear support members, parallel elements for securing said members together and for maintaining the same in proper spaced relation, a pair of cooperating relatively movable steel guiding elements pivotally mounted on two of said securing elements between said support members, and a torsion spring encircling a third securing element and engaging said guiding elements for automatically swinging the latter toward their released non-guiding position.

75

14. In a drill steel guide, a support including spaced front and rear support members, parallel elements for securing said members together and for maintaining the same in proper spaced relation, a pair of cooperating relatively movable steel guiding elements pivotally mounted on two of said securing elements between said support members, springs encircling the securing elements on which said guiding elements are pivotally mounted for yieldingly holding said guiding elements in steel guiding position, and a torsion spring encircling a third securing element and engaging said guiding elements for automatically swinging the latter toward their released non-guiding position.

15. In a drill steel guide, a support, a pair of cooperating relatively movable steel guiding elements mounted on said support for pivotal and translatory movements, means for locking said guiding elements to said support in steel guiding position and releasable upon translatory movement of said guiding elements in one direction, and a common torsion spring arranged on said support intermediate the pivots provided by said guiding elements and engaging both of the latter

for swinging said guiding elements into their non-guiding position upon translatory movement of said guiding elements into a position wherein said locking means is released.

16. In a drill steel guide, mounting means, a pair of relatively movable guide arms supported by said mounting means for pivotal and translatory movements with respect thereto, means for locking said guide arms to said mounting means in guiding relation with a drill steel and releasable upon translatory movement of said arms in one direction with respect to said mounting means, and resilient means for moving said arms translationally in the opposite direction yieldingly to hold said arms in locked position and for swinging said arms about their pivots out of guiding relation with the drill steel when said arms have moved translationally in the opposite direction into a position wherein said locking means is ineffective, said resilient arm swinging means comprising a common torsion spring engaging and acting between said guide arms.
